TRACTION STIRRUP

George W. Hawley, Colorado Springs, Colo., assignor to Scanlan-Morris Company, Madison, Wis.

Application November 29, 1932, Serial No. 644,767

4 Claims. (Cl. 128—84)

My invention relates to surgical apparatus, and particularly to a device for supporting the foot of a patient while bandaging or placing same in a cast.

5 An important object of the invention is to provide such a device that is useful in fracture cases, and to afford sufficient traction to enable the surgeon to align the fractured sections of the bone through tension applied to the fractured member.

Other objects are to provide in such apparatus means for a strong, durable grip on the ankle that will not bind, that does not constrict circulation, which does not cause pain 15 and does not injure the skin, and is readily removable.

Still another object is to provide in an invention of the character mentioned, a bandage or strap that can be removed without cutting the 20 cast.

Further objects reside in novel details of construction and in novel combinations and arrangements of parts, which will appear in the course of the following description.

25 In the drawing, like reference characters designate similar parts in the several views.

Figure 1 is an isometric view of an embodiment of the present invention.

Figure 2 is an enlarged side elevation, looking 30 in the direction of the arrow A in Figure 1.

Figure 3 is an enlarged section taken on the line 3—3 of Figure 1.

Figure 4 is a reduced elevation, similar to Figure 2, illustrating the use of the invention.

35 Referring more in detail to my invention, the reference character 5 designates a standard, such, for instance, as is found on a surgical table of the character shown and described in my co-pending application Serial No. 644,770, filed November 29, 1932.

A sleeve 6, slidably mounted on the standard, is held in desired positions by a set screw 7. The sleeve has apertured, spaced ears 8, which carry a locking bolt 9. A stirrup 10 is provided with an apertured lug 11 that is inserted between the ears 8 and holds the stirrup in desired positions, through the intermediary of the bolt 9, which is inserted through the aligned apertures of the ears and lug.

50 The stirrup proper is formed to provide a yoke adapted to embrace the foot of the patient and having a head-piece or cross member 12, upon which the lug 11 is integrally formed, and arms or side members 13 and 14 that are pivoted on the head-piece at 15 and 16 respectively.

The arms 13 and 14 have horns 17 and 18 respectively, projecting beyond the pivots 15 and 16. The shoulders of the head-piece between the lug and the horns have been designated 19 and 20.

The projecting end of the arm 13 has double hooks 21 and 22, and the projecting end of the arm 14 has double hooks 23 and 24. The hooks are mounted in knuckles 25 and 26 at the ends of the arms 13 and 14 respectively.

The details of the pivotal mounting for the arms on the head-piece 12, are shown in detail in Figure 3. The head-piece has at its ends shouldered tenons 27, the shoulders of which are curved, as indicated in Figure 1, to receive 70 rounded fingers 28 on the arms at either side of the tenons 27.

The manner of wrapping the ankle of a foot in the stirrup is considered one of the unique features of the invention and will be described 75 in connection with the use of the invention.

In the drawing, a foot 29 is shown in the stirrup and positioned against a foot rest 36. The leg has been indicated by the numeral 30. Without any attempt to fully illustrate the leg, 80 the tibia bone is suggested at 31.

In the use of the invention, the stirrup is adjusted to the desired height on the standard and held in such position by the set screw 7. The stirrup is then pivotally moved in a vertical 85 plane to the desired angle and held there by the locking bolt 9.

The foot is then placed in the stirrup, preferably with the rear portion of the arch resting on the head-piece. This gives sufficient space 90 between the ball of the foot and the stirrup for the application of bandages or plaster for a cast. A strap or tape 32 is then laced around the stirrup and ankle in the following manner: Starting at the upper left hand corner of the 95 stirrup, as it is shown in Figure 1, the strap passes around the shoulder 19, underneath the stirrup as shown, through the hook 22, across one side of the ankle, as indicated at 33, through the hook 24, under the stirrup, around the 100 shoulder 20, along the top of the arm 14 as shown, through hook 23, across the other side of the ankle, as indicated at 34, through hook 21, along the top of the arm 13 to the place of beginning, where the ends of the strap are tied 105 to each other.

The foregoing wrapping may of course be repeated as many times as desired. It will be noted, however, that the straps do not criss-cross and that the straps are not wound con- 110

tinuously around the ankle, thus facilitating removal of the foot, after the cast or bandage is applied.

When a cast is applied, the portions 33 and 34 of the strap are encased in the cast. After the cast has set and it is desired to remove the foot, the portions of the strap near the pivots 15 and 16, which are exterior of the cast, are severed, and the exposed parts of the strap are cut away.

10 The exposed parts include those parts between the hooks and horns. The arms of the stirrup are then swung outward from the foot, and the foot may be removed. The pieces of the strap remaining in the cast can be withdrawn by pulling gently on one end of same, and no injury will result to the cast.

15 The horns 17 and 18 prevent the strap from slipping off the shoulders of the head-piece, and, if desired, the ends of the strap may be tied to one of the horns.

20 The present invention not only provides more traction than heretofore, but also simplifies applying bandages or a cast, and simplifies removal of the foot from the stirrup. Changes may be 25 made in the details without departing from the spirit and scope of the invention. It must be borne in mind that the device shown and described hereinbefore is merely an embodiment of the invention and of the foregoing objects.

25 30 What I claim and desire to secure by Letters Patent is:

35

150

1. In surgical apparatus, a foot stirrup having a cross member and side members on the cross member, one end of the side members having horns projecting beyond the cross member and the other end having double hooks.

80

2. In surgical apparatus, a foot stirrup having side members provided with horns and hooks at opposite ends, and a strap extending from one horn, passed through one of the hooks on the same side member, across one side of an ankle of a foot in the stirrup, through a hook on the opposite side of the ankle from the first-mentioned hook, around the other horn, through a hook on the same side, across the other side of the ankle from that mentioned, through a hook on the first side and back to the first horn.

85

3. In surgical apparatus, a foot stirrup comprising a yoke, inclusive of side members pivoted to swing away from a foot embraced by the yoke, the side members having horns and hooks at opposite ends for the application of a strap in restraining relation to the foot.

90

4. In surgical apparatus, a foot stirrup comprising a yoke, inclusive of side members pivoted to swing away from a foot embraced by the yoke, the side members having at opposite sides of their pivotal axes, horns and hooks for the application of a strap in restraining relation to the foot.
